[57] CLAIM

The ornamental design for a concrete deck insert, as shown and described.

DESCRIPTION

FIG. 1 is a front elevational view of the front of a concrete deck insert, showing my new design, the rear elevational view being a mirror image thereof;

FIG. 2 is an elevational view of one side, the view of the opposite side being a mirror image thereof;

FIG. 3 is a top plan view;

FIG. 4 is a bottom plan view;

FIG. 5 is a partial medial sectional view with the threaded rod and cap fully shown, a portion of said rod being omitted for ease of illustration, the broken line showing of the steel decking for concrete floors for illustrative purposes only;

FIG. 6 is a view similar to FIG. 5 of a modified embodiment of the design of FIG. 1, the only difference being the length of the threaded rod, again, the broken lines being for illustrative purposes only.
